UNITED STATES PATENT OFFICE.

HARRY E. KERR, OF CLEVELAND, OHIO, ASSIGNOR TO THE CLEVELAND GAS BURNER AND APPLIANCE COMPANY, OF CLEVELAND, OHIO, A CORPORATION OF OHIO.

GAS BURNER FOR HEATING PURPOSES.

Application filed December 8, 1924. Serial No. 754,541.

My invention relates to an improvement in gas burners for heating purposes and the present burner is particularly constructed to permit it to be operated at its maximum efficiency and capacity under conditions which might otherwise impair its usefulness, especially in a restricted chamber or a narrow elongated casing. Among other things my conception is to provide a burner adapted to produce a series of spreading columns of flame in close contiguity, either lengthwise or diagonally of the burner, using separate pairs of reversely-inclined jets or nozzles placed on the bias or at a slant between two parallel gas distributing pipes or a manifold comprising two parallel gas distributing members. These spreading columns of flame are caused to burn parallelly with each other but diagonally or longitudinally of the burner, and a further purpose is to produce perfect combustion and the maximum size of heating flame in separate places on the bias or longitudinally as described within a minimum length and width of space.

5

In the accompanying drawings, Fig. 1 is a top view of my improved burner, and Fig. 2 is a side elevation thereof, the dotted lines representing the approximate size and shape 10 of the flame. Fig. 3 is an enlarged sectional view transversely of the burner on slanting line 3—3 of Fig. 1.

15

The burner comprises a tubular manifold which in the present instance consists of a single casting having two parallel branches or tubes 2 and 3 connected together at their corresponding ends by a cross tube 4 having an intake extension 5 at its middle adapted to connect with a gas supply pipe. A conveniently rounded portion 6 opposite intake extension 5 promotes uniform distribution of the incoming gas to both legs or branches of the burner. The opposite or outer ends of these burners are rigidly connected together 20 by a web 7, and further rigidity may be obtained by connecting the branches together intermediate their ends by one or more similar webs 8, the number used being dependent upon the length of the burner.

25

In certain heater appliances where the space is restricted but a high temperature and perfect combustion is required I have found it desirable to employ a burner embodying reversely inclined jets, and in practice these jets must be properly proportioned

and spaced apart at a predetermined distance to effect the best results. The present burner has been devised to permit the use of said jets in such appliances without any changes in proportions or settings of each pair of jets, the burner being made narrow in width for satisfactory use in such appliances. Thus the parallel branches 2 and 3 are formed with flattened bosses 9 at uniformly spaced intervals of their length, the flat faces being inclined upwardly at an angle of approximately 45° and arranged in reversely inclined order on the opposed sides of said parallel branches. These bosses having inclined faces are also placed in staggered relation 60 oppositely on the branches so that the reversely-inclined surfaces face each other in pairs on diagonal lines viewed from the top of the burner. Each boss is provided with a screw threaded opening at right angles to 65 its face and separate brass jets or nozzles 10 are screwed into said openings, thereby providing a pair of co-acting gas jets extending upwardly toward each other at approximately right angles and spaced apart at 70 75 their mouth ends centrally above the open space between the branches or tubes 2 and 3, respectively. Each jet or nozzle 10 has a cup-shaped intake 11 communicating with a small gas discharge orifice 12 in the base of 80 the nozzle, and the outer and major length of the nozzle is formed with a larger bore 14 having lateral air intake openings 15 adjacent orifice 12. Each pair of jets extend 85 toward each other on a line which extends diagonally across both branches or tubes, or in other words, diagonally in respect to the longitudinal median line of the burner. The successive pairs of jets are also parallelly arranged so that no interference in commingling the gases and air between each pair can 90 occur. Thus the burner comprises a series of co-acting pairs of jets extending diagonally of the burner, each pair being parallel with the other pairs of jets at spaced intervals lengthwise thereof, whereby in operation two fine streams of gases are jetted at high velocity into confluence between and above each pair of nozzles, and a predetermined amount of air is drawn through the 95 same nozzles with the gas to produce an independent column of flame between the legs or branches, which flame is substantially ovoidal in cross section. The diagonal arrangement of the jets spreads this flame diag- 100 105 110

- onally of the burner and in a longitudinal direction which is advantageous when the chamber or casing is relatively narrow and also advantageous in providing rapid initial ignition of the gas in starting operations. As shown, the jets or nozzles of each pair have their axes extending in the same vertical plane so that the gas and flame spreads at right angles to such axes. A slight offset relation of the jets will tend to spread the flame at an angle other than a right angle and the flame may thereby be caused to spread to a greater degree in a longitudinal direction, if desired.
- 15 What I claim is:
1. A gas burner for heating purposes, comprising a single cast metal manifold having straight parallel branches united by webs, and a series of tubular gas and air commingling jets mounted upon each branch and arranged in staggered relation oppositely on said branches in pairs, each pair of jets extending diagonally of the burner and projecting upwardly at an inclination toward each other to effect a commingling of

separate streams of gas intermediate said branches, and all of the separate pairs of jets being parallel to produce separate sheets of flame spreading diagonally of said burner on parallel lines.

2. A gas burner for heating purposes, comprising parallel gas distributing tubes, a series of air and gas commingling nozzles mounted upon each tube and arranged in pairs oppositely on said tubes and extending upwardly at an inclination toward each other, each pair of co-operating nozzles extending on diagonal lines across said burner and adapted to bring separate streams of combustible mixtures together to spread a single sheet of flame obliquely in respect to the parallel tubes and parallel with similar sheets of flame created by each pair of co-operating nozzles, the separate pairs of nozzles being all parallel diagonally of the distributing tubes.

In testimony whereof I affix my signature.

HARRY E. KE
